UNITED STATES PATENT OFFICE.

EDSON J. SMITH, OF BOSTON, MASSACHUSETTS, ASSIGNOR TO JOHN CARTER,
OF NEWTON, MASSACHUSETTS.

PAPER-CUTTER.

SPECIFICATION forming part of Letters Patent No. 735,166, dated August 4, 1903.

Application filed May 12, 1902. Serial No. 106,857. (No model.)

To all whom it may concern:

Be it known that I, EDSON J. SMITH, a citizen of the United States, residing at Boston, in the county of Suffolk and State of Massachusetts, have invented a new and useful Improvement in Paper-Cutters, of which the following is a full, clear, and exact description, reference being had to the accompanying drawings, forming a part of this specification, in explaining its nature.

The invention relates to an improved paper-cutter, and essentially to the means by which cards may be severed from a strip of cardboard and simultaneously may be cut with rounding corners.

It comprises, therefore, primarily a punch and die of improved construction the cutting edges of which are adapted not only to sever the cards corresponding as the strip is fed along, but also to finish each severed card by rounding its corners contiguous to the inner cut edge and preparing the card next in order by rounding the corners of the strip at the point of cutting.

The invention comprises also means for the retention and adjustment of the aforesaid punch and die, together with an improved mechanism for actuating the punch.

The details of construction may best be seen and described by reference to the drawings, wherein—

Figure 1 shows my device in front elevation from the lines 1 1 of Fig. 2. Fig. 2 is a vertical section upon the line 2 2 of Fig. 1. Fig. 3 is a horizontal section on the line 3 3 of Fig. 1. Fig. 4 shows the punch in detail and the means for its retention. Fig. 5 shows a strip of paper or cardboard severed in part section by my improved cutter and showing especially the rounding corners of the severed card.

Referring to the drawings, A represents a frame which is adapted to sustain several parts of my invention in proper relation of position and adjustment to one another. It is of perpendicular extension and comprises the upper plate a, to the side of which is attached the mechanism for manipulating the punch, the sections a' extending down at either side to form a central opening a², through which the work may be fed to the

punch and die, and the integral sides a³, which, with the shelf-pieces a⁴, provide a rectangular recess in which the die-holder is adapted to be contained.

The frame A is held in place by any suitable means of support. I have shown it as extending from and of integral attachment with a bed or table A', upon which the strip of paper or cardboard is placed in readiness to be fed through the opening a² and severed. (See Fig. 2.) This, however, is only a convenient order of arrangement. The frame A may make connection with any other support, and even its own construction may well be varied.

B represents the die, and C the punch; B' C', respectively, their holders, by which they are not only held in permanent position of adjustment, but may be brought together in their conjoint relation.

The holder B' is made rectangular in shape, so as to be contained within the sides a³ of the frame and to rest upon the seats a⁴ provided for it. It is made relatively heavy, with a rectangular vertical recess within its center, in which the die is contained. It may be of integral formation; but as represented its sides are completed by the detachable side piece b, which has suitable screw connections b'. When in place, the holder extends back, so that its interior edge will be contiguous with the edge of the bed or table A' and their upper surfacings be continuous in order that the paper strip may be freely fed to the die which is contained within the recessed interior of the holder.

The die B is made in two detachable sections b². These sections b² are made of strips of steel and have, essentially, the upper surfaces b³ continuous with the top of the holder and provided with the cutting edges b⁴ and rounded cutting ends b⁵. They are held in place by screws b⁶, coming through the opposite sides of the holder, and their separation and adjustment is such that a narrow passage will be formed between their cutting edges b⁴, through which the blade c of the punch C will pass, and its cutting edges c' will coincide with the edges b⁴ of the die, and its rounding walls c² will be contiguous with the rounding ends of the die-sections, so that

the paper or cardboard when placed over the die will be cut in lines corresponding with the contiguous or coinciding edges of the punch and die. This is best seen in Fig. 5, where I have shown a strip of paper or cardboard D separated in part section into a card D'. The strip of cardboard, it is to be noted, is of the same width as the card to be cut, and on being fed crosswise the die there is punched or 10 cut out a narrow section d rounding outwardly at either end. By the stamping out of this or like section the card D' not only becomes severed from the strip, but its edges contiguous with the stamped-out sections are 15 made rounding, while the end of the strip is left with rounding corners, the practical result being that after the end of the strip has once been formed by the cutting of the waste piece D² the cards may be cut with rounding 20 corners upon a continuous feeding of the strip to the die, the back edge of the severed card being formed with the front edge of the next in order.

In order that the cards may be severed of 25 uniform width, suitable gage-clamps a⁵ may be employed, as appear from the drawings.

The punch C, besides its blade c, which has double cutting edges c' and outwardly-rounding walls c², as above described, may be of 30 any suitable construction. Its holder C' comprises the upper cross-bar c³ and the two downwardly-extending bars c⁴ of preferably integral attachment, the punch being extended between them and along beneath the cross- 35 bar c³. The punch is detachably held in place by the screws c⁵, extending through the vertical bars c⁴, while a bead c⁶ extends into a groove c⁷ along the under side of the cross-bar, helps the retention, and secures accuracy 40 of adjustment. In order that the cutting edges of the punch may be in alinement with the cutting edges of the die and be brought into conjunction with them when the punch is depressed, the bars c⁴ are extended down 45 into the recesses b⁷, cut through the die-holder B', and which are in such relative position and the bars fit with such accuracy of adjustment that not only is the punch-holder supported, but as the bars fit down into the 50 recesses the punch is brought in perfect adjustment to conjoin with the die. The blade of the punch, it is to be observed, has a shearing edge, so that the paper or cardboard is practically cut instead of stamped out as the 55 punch is depressed. As the blade extends along between the separated sections of the die the waste piece d stamped or cut out is forced down through the opening between the edges of the die and falls through the hole 60 low interior of the holder.

I have already referred to the punch and sections of the die as being detachable. This is in order that they may be of different sizes or shapes, dependent upon the widths of the 65 strips of paper or cardboard or upon the size or configuration of the card to be cut therefrom. By being made detachable the punch

and die-pieces may also be taken out and their cutting edges sharpened when occasion demands or any other repair obtained.

The holder C' and so the punch C are held in normal elevated position by the coiled spring b⁸, which rests upon the holder B' and bears up against the exterior ends of the cross-bar. The spring envelops and is supported by the 75 rods b⁹, which extend up from the holder B' and through the ends of the bar c³. The spring is therefore retained in a permanent position of adjustment and is adapted to become compressed when the punch, or rather 80 its holder, is pressed down and to exert a lifting action upon it with the release of the operating pressure.

The punch C is pressed down by means of the plungers E E', working through the tubular bearings a⁶, extending from the frame. These tubular extensions a⁶ are in line with the horizontal cross-bar c³ of the punch-holder, so that the plungers rest against, and acting simultaneously, press down the cross-bar at either end, and in order that there may be an equal distribution of pressure along the length of the bar, and the punch evenly pressed down along its double cutting edge.

The plungers are actuated by the toggle or 95 knuckle links e e' of the plunger E, and the knuckle links e² e³ of the plunger E'. The link e is pivoted within the cleft-head of plunger E and the link e' at the point e⁴ between the overhang of the arm e⁵ and the frame side 100 a, while the link e² is pivoted within the cleft of the plunger E' and its connecting-link e³ at the point e⁶ between the overhanging arm e⁷ and the side of the frame. Connecting with the toggle-links by the same pivots which 105 connect them are the thrust-links e⁸ e⁹, which are adapted to straighten the toggle-joints, and so press down the plungers. For obtaining their movement I have shown a bent lever which comprises the operating-arm e¹⁰, 110 extending from the side of the frame, and the angular arm extensions e¹¹ e¹². The angular arms e¹¹ e¹² are pivoted at the center of their connection at the point e¹³ between the overhanging arms e¹⁴ and the side of the frame, 115 so that practically the lever-arm is fulcrumed at this point and when operated its arms e¹¹ e¹² rotate from the point e¹³ as a center, and as the one is thrown outward to the right the other is rotated to the left. The ends of the thrust-links e⁸ e⁹ are pivoted to the lever-arm extensions e¹¹ e¹² by pivot-pins e¹⁵ e¹⁶, which 120 completes the combination of parts, and consequently when the operating lever-arm e¹⁰ is drawn down its arms e¹¹ e¹² are rotated, 125 each simultaneously through its connecting-links e⁸ e⁹, respectively, straighten out the toggles, and the plungers are depressed.

In order that the lever-arm may be returned and retained in a normal operative position, 130 I have made the springs b⁸ of sufficient tension that by bearing up against the cross-bar c³ they may also push back the plungers and so bend the toggles, which through their con-

necting-links $e^8 e^9$, respectively, throw back the lever-arm to its normal operative position.

The arrangement, proportion, and pivotal points of the parts are such that a most powerful compressing action is obtained, as well as an evenness and facility of movement.

Having thus fully described my invention, I claim and desire to secure by Letters Patent 10 of the United States—

1. In a paper-cutter, a punch having a blade formed outwardly rounding or flaring in reverse directions at either end, and a die to conjoin with said blade in order that a strip of paper or the like fed between the said punch and die may be severed in a manner substantially as described.

2. In a paper-cutter, a punch having a blade with a shearing edge formed outwardly rounding in reverse directions at either end, and a die having cutting edges separated to receive between them the said blade of the punch, but with a placement and configuration to conjoin with the said cutting edges thereof in order that a strip of paper or the like fed between the said punch and die may be severed in a manner substantially as described.

3. In a paper-cutter, a frame offering a housing for the removable holders of a cutting punch and die, said holders and said punch and die carried by the same and made detachable therefrom, means for so connecting said holders that the punch-holder will move when depressed in true parallel lines relatively to the die-holder that a proper correlation between the cutting edges of the punch and die may be obtained, a plurality of plungers for evenly depressing the punch-holder, and means for simultaneously actuating the plungers.

4. In a paper-cutter the combination of a frame, a cutting-punch and die-holders therefor, carried by said frame, and which are joined to approach each other on true paral-

lel lines, that a proper correlation between the cutting edges of the punch and die may be obtained, plungers carried by the frame for evenly depressing the punch-holder, toggles for simultaneously actuating said plungers, and a bent operating-lever having angular arm extensions pivoted to the frame at the center of their connection, with thrust-links connecting the said arm extensions with the said toggles in order that the same may become straightened and the plungers depressed, substantially as described.

5. In a paper-cutter the combination of a frame, a cutting-punch and die-holders therefor, carried by said frame, and which are joined to approach each other on true parallel lines that a proper correlation between the cutting edges of the punch and die may be obtained, plungers carried by the frame for evenly depressing the punch-holder, toggles for simultaneously actuating said plungers, and a bent operating-lever having angular arm extensions pivoted to the frame at the center of their connection, with thrust-links connecting the said arm extensions with the said toggles in order that the same may become straightened and the plungers depressed, and a work-returning spring or springs having placement between the punch and die-holders aforesaid, substantially as described.

6. In a paper-cutter the combination of a frame, a cutting-punch and die-holders therefor, carried by said frame, and joined to approach each other on true parallel lines, plungers carried by the frame for evenly depressing said punch-holder, means for simultaneously actuating said plungers, and a work-returning spring or springs having placement between the die and punch-holders, substantially as described.

EDSON J. SMITH.
